United States Patent Office

Des. 190,346
Patented May 16, 1961

190,346

PHOTOCOPYING APPARATUS

Frederick H. Frantz, Vestal, and Joel W. Bravo, Binghamton, N.Y., assignors to General Aniline & Film Corporation, New York, N.Y., a corporation of Delaware

Filed Dec. 8, 1960, Ser. No. 63,153

Term of patent 14 years

(Cl. D61—1)

The single figure is a perspective view of a photocopying apparatus showing our new design.

The rear, not shown, is conventional and the side opposite that shown is substantially the same as that shown.

We claim:

The ornamental design for a photocopying apparatus, substantially as shown and described.
